UNITED STATES PATENT OFFICE.

MERLE P. CHAPLIN, OF FAIRFIELD, MAINE, ASSIGNOR TO KEYES FIBRE COMPANY, OF FAIRFIELD, MAINE, A CORPORATION OF MAINE.

LUBRICATING-BEARING.

1,225,577.

Specification of Letters Patent.

Patented May 8, 1917.

Application filed August 8, 1913. Serial No. 783,695.

To all whom it may concern:

Be it known that I, MERLE P. CHAPLIN, citizen of the United States, residing at Fairfield, county of Somerset, State of Maine, have invented an Improvement in Lubricating-Bearings, of which the following description, in connection with the accompanying drawing, is a specification, like characters on the drawing representing like parts.

This invention relates to improvements in lubricating bearings, particularly those used for the pivots of arms supporting certain mold members in machines for molding articles from pulp, such as those illustrated and described in the prior patents to Martin L. Keyes No. 759,616, granted May 10, 1904 and No. 788,138 granted April 25, 1905.

In a machine of this character a traveling mold is employed, said mold being made in two parts, one of which is pivoted with respect to the other. The mold parts are hollow or chambered, and connections are made to said chambers through the arms supporting the mold parts and are to enable the air in said chambers to be exhausted or compressed as required in the operation of forming articles from pulp.

At one period in their travel the parts of the mold are pressed together by a powerful compressing mechanism in order to compact the pulp into the desired shape, and to reduce the amount of water therein. The machine is run at a high speed and it is therefore necessary that the parts shall be so constructed as to operate accurately with rapidity. The machine must of necessity be of strong construction to stand the wear and tear of the moving parts, and the powerful compression to which the mold parts are subjected. The mold parts, or at least one of them, in its travel passes through a vat of liquid pulp, and the pulp together with other foreign matter is splashed more or less over the entire machine, particularly over the mold carrying arms, and consequently runs down freely upon the pivotal joint connecting the two arms of the mold.

It is particularly necessary that the pivot arm carrying the movable mold part shall swing back and forth on its pivot with great accuracy in order that the parts of the

mold may come into exact juxtaposition, so that the molded article may be formed properly and of uniform thickness. It is also necessary that this pivotal joint shall be kept well lubricated and that foreign matter shall be wholly prevented from entering the bearing. It is found in practice, where the water from the liquid pulp has obtained access to the bearing of this pivotal arm, that the bearing rapidly wears away, in a short time producing a looseness which prevents the proper registry of the molds. This necessitates the stopping of the machine and the replacing of the parts, causing a loss of time and considerable expense in supplying new parts. This and other considerations which will be apparent from an examination of the machine in question and its workings, render the joint portion between the pivot and the fixed mold carrying arms a vital feature of this machine.

The present invention relates to this feature. It comprises a form of joint which has an extended bearing surface, possesses great strength and secures accurate registry of the mold parts; it provides for a thorough and continuous lubrication of the bearing, and the manner in which the lubricant is introduced into the bearing prevents the entry of water or other foreign matter, or if by chance any water or foreign matter obtains access to the bearing, it is promptly forced out. The joint made according to my invention is of a simple character, is easily dismantled and replaced and has been found in practice to be exceedingly efficient, increasing the life of the machine in which it has been used, a considerable period.

The invention will more fully appear from the accompanying description and drawings, and will be particularly pointed out in the appended claims. The drawings represent only the joint portion and such parts as are connected respectively to the rotary frame of the machine, and to the arm of the mold.

In the drawings,

Figure 1 is a front elevation showing the bearing and the yoke connecting the same to the mold arm.

Fig. 2 is a plan view showing in section, the hollow arm of the relatively stationary member of the mold, and a stiffening ring

connected thereto, and to which the joint embodying this invention is attached.

Fig. 3 is a sectional view through the joint.

5 Fig. 4 is an end view of the joint, with the cap removed.

Fig. 5 is a vertical sectional view through the end of the joint showing the relative relation of the oil-cup, cap for the bearing 10 and the ducts for supplying oil to said bearing.

Fig. 6 is an end view of the part which connects the oil-cup to the cap, as shown in Fig. 5.

15 It is unnecessary to describe for the purpose of this invention, the general machine to which it relates, since the same is fully set forth in the above mentioned patents.

The parts of the present invention, in the 20 form illustrated herein, include a U-shaped member 1, adapted to extend around the arm 2 of the fixed mold member, and to be bolted to the stiffening ring 3 of the machine by bolts 4, in the same manner as the 25 joint, for the same purpose, is secured to the ring of the machine illustrated in said Patent #759,616. The U-shaped member 1 is provided with a boss 5, in which a shaft 6 is fixedly secured by a set screw 7, the ends 30 of said shaft projecting a considerable distance beyond each end of said boss. Mounted upon the ends of the shaft and abutting against the ends of the boss are sleeves 8, each of which is provided with a thickened 35 portion 9 to which a yoke 10 is rigidly secured by machine screws 11. The yoke 10 is provided with flanges 12 at each end which fit over and embrace the projecting portions of the sleeves above described, and 40 serves to secure said sleeves rigidly from endwise movement upon the shaft 6. The yoke 10 is an integral portion of an arm 13, which supports and carries the movable part of the mold. The arm 13 is hollow and 45 is provided with the usual air passage 14, leading to the mold chamber for the purpose of enabling the air in said chamber to be exhausted or compressed, as required in the operation of the machine. Caps 15 are 50 screwed upon the ends of the sleeves 8 and are normally forced tightly against the ends of the shaft 6. In practice the sleeves are of such a length as to allow the shaft to project a short distance beyond the end of the 55 sleeve, the space between the sleeve and the nut being taken up with several thin washers to allow an adjustment in case of wear.

Means are provided for introducing oil or grease through the caps and through or 60 longitudinally of the shaft, in such a manner as to supply a lubricant uniformly to substantially all of the relatively rotatable surfaces of the bearings. The lubricant may be supplied through the cap 15 by any suitable force-feed mechanism, or by any other 65

means which will insure a continuous and free supply of lubricant. In Fig. 3 grease guns 16 are shown, which are attached to the caps 15 and are so arranged as to deliver the lubricant at the axis of the shaft.

70 The shaft is provided at each end with ducts 17 extending axially inward a short distance from the ends of the shafts. Longitudinal slots or orifices 18 lead from these ducts to the surface, three or more of such slots being provided whereby the lubricant will be supplied constantly and uniformly throughout substantially all of the relatively rotating surfaces of the shaft and sleeves. By virtue of this construction a constant 75 flow of lubricant is maintained from the ends of the bearings toward the ends of the boss 5.

Any water or other foreign material 80 which might enter between the boss and sleeves will be excluded or promptly forced out and thereby prevented from injuring the surfaces of the bearing. In practice it is found that when a thin line of lubricant is 85 found to be present around the shoulder 90 of the boss 5, against which the sleeves 8 abut, the operator is assured that there can be no water or other foreign matter present in the bearing.

90 In some classes of machines there is not 95 sufficient room for forced feed lubricators to be secured to the caps axially of the shaft as shown in Fig. 3. I have therefore devised a lubricator which may be so secured to the cap that the reservoir will be maintained at an angle, preferably a right angle, to the axis of the shaft. The device is so constructed, however, that the lubricant will be supplied to the axial duct in the shaft.

100 This modified form of feeding device for 105 the lubricant is shown in Fig. 6. In this form the cap 15 is provided with a projection 19, upon which a cylindrical cup 20 is secured by a set screw 21. The cup 20 is provided with a projection 22 to which a 110 grease gun or other reservoir 23 is secured. The cup 20 provides an annular recess 24, which communicates through an opening 25 with the grease gun or reservoir 23. The 115 cap 15 is provided with a series of two or more ducts 26, which lead from the annular recess 24 to a central opening in the cap which in turn communicates with the axial duct 17 of the shaft 6.

120 It is to be understood that the particular forms and devices for supplying lubricant above described, are not the only ones which are adapted to be used in connection with my invention but are illustrative merely of the forms which I have found in practice to 125 be desirable.

125 By my invention, as above described, I have provided a joint which possesses great strength and rigidity because of the extended bearing surfaces for the rotatable parts, 130

and of their location upon both sides of the supporting boss.

I have provided a means for uniformly supplying a lubricant to the relatively rotating bearing surfaces and have also supplied a means whereby said lubricant will be so fed to the bearing as to exclude any water or other foreign matter from entering the bearing. The construction thus described has been found to work with great satisfaction, and to secure the desired results under the trying conditions to which such a device is subjected in a machine of the character in question.

Having fully described my invention what I claim as new and desire to secure by Letters Patent is:—

1. In an apparatus of the class described, a fixed member provided with a laterally extending shaft having an axial duct and slots, substantially equal in length to the bearing portion of the shaft, leading from said duct to the surface of the shaft, a member rotatably mounted upon said shaft and bearing at one end against said fixed member, a cap secured to the opposite end of said rotatable member and engaging the end of the shaft, means for supplying lubricant through said cap to said duct and means for forcing the lubricant toward the bearing between the fixed and rotatable members whereby the shaft bearing will be protected against entry of foreign matter.

2. In an apparatus of the class described, a fixed member provided with a laterally extending shaft having an axial duct and slots, substantially equal in length to the bearing portion of the shaft, leading from said duct to the surface of the shaft, a member rotatably mounted upon said shaft and bearing at one end against said fixed member, a cap inclosing the opposite end of said rotatable member and tightly engaging the end of said shaft, means for supplying a lubricant axially through said cap to the duct in the shaft and means for forcing the lubricant toward the bearing between the fixed and rotatable members whereby the shaft bearing will be protected against the entry of foreign matter.

3. In an apparatus of the class described, a fixed member provided with a laterally extending shaft having an axial duct and slots, substantially equal in length to the bearing portion of the shaft, leading from said duct to the surface of the shaft, a member rotatably mounted upon said shaft and bearing at one end against said fixed member, a cap inclosing the opposite end of said rotatable member and engaging tightly the end of the shaft, means for supplying a lubricant through a plurality of apertures in said cap to the axial duct in said shaft and means for forcing lubricant simultaneously through said passages to said axial

duct, whereby constant lubrication of the bearing between said shaft and said movable member will be maintained.

4. In an apparatus of the class described, a fixed member, a shaft secured thereto, a member having a yoke rotatably mounted upon the ends of said shaft, and means for introducing a lubricant at the ends of said shaft and for distributing it uniformly throughout the relatively rotatable surfaces and causing the same to flow toward the fixed member, whereby the shaft bearings are protected against foreign matter entering through the bearings between the fixed and rotatable members.

5. In an apparatus of the class described, a stationary member, a shaft secured thereto, a member having a yoke provided with sleeves rotatably mounted at the end of said shaft caps secured to said sleeves and inclosing the ends of said shaft, means for introducing a lubricant through said caps for distributing the lubricant uniformly, substantially throughout the relatively rotatable surfaces and for causing a flow of said lubricant toward the stationary member, whereby the shaft bearings are protected against foreign matter entering through the bearings between said fixed and rotatable members.

6. In an apparatus of the class described, a stationary member, a shaft secured thereto, sleeves rotatably mounted on the ends of said shaft, projections upon said sleeves, a member having a yoke secured to said sleeves and having flanges engaging the outer faces of said projections, and securing said sleeves from endwise movement on said shaft, means for forcing a lubricant between the shaft and rotatable member endwise of the shaft and toward or through the bearing between the fixed and rotatable members, whereby the shaft bearings are protected against foreign matter entering through the bearings between said fixed and rotatable members.

7. In an apparatus of the class described, a stationary member, a shaft secured thereto, a member having a yoke provided with sleeves mounted on said shaft, caps mounted on said sleeves and inclosing the ends of said shaft, ducts leading through said caps and axially into said shaft, distributing orifices connecting with said ducts and leading therefrom to the surface of said shaft, means for forcing a lubricant into said duct, whereby a uniform flow of the lubricant will be maintained between the relatively rotating bearing surfaces and toward the stationary member.

8. In an apparatus of the class described, a stationary member, a shaft secured thereto, a yoke having sleeves mounted on said shaft, caps mounted on said sleeves and inclosing the ends of said caps, lubricant ducts

leading through said caps and axially into said shaft, radial slots in said shaft extending substantially throughout the length of the bearing surfaces connecting with said ducts and leading to the surface of the shaft, and means for continuously supplying a lubricant to said ducts whereby the bearings will be uniformly lubricated and a continuous flow of lubricant toward the stationary member maintained.

9. In an apparatus of the class described a shaft having an axial duct and slots leading therefrom to the surface of the shaft, a member rotatably mounted upon said shaft, a cap secured to said rotatable member inclosing the end of said shaft and having a central orifice connecting with the axial duct in said shaft, a reservoir for a lubricant affixed to said cap at an angle to the axis of the shaft, ducts leading from said reservoir to the central orifice in said cap and means for forcing the lubricant into said ducts.

10. In an apparatus of the class described a shaft having an axial duct, and slots leading therefrom to the surface of said shaft, a member rotatably mounted on said shaft, a cap secured to said rotatable member inclosing the end of said shaft and having a central orifice, a reservoir for a lubricant affixed to said cap at an angle to the axis of said shaft and having a duct connecting with the axial duct of said shaft, means variable in thickness interposed between the end of said rotatable member and said cap whereby said cap may be advanced to compensate for wear and to maintain tight con-

tact between the end of the shaft and the cap so that the effective force of the lubricant feeding mechanism will be constant.

11. In an apparatus of the class described, a shaft, a member rotatably mounted thereon, a cap having a central orifice secured to said rotatable member bearing on the end of said shaft, a reservoir for a lubricant fixed to said cap at an angle to the axis of said shaft, and a plurality of removable thin washers adapted to fill the space between the end of the rotatable member and said cap whereby adjustment to compensate for wear may be obtained by removing one or more of said washers and advancing said cap.

12. In an apparatus of the class described, a shaft, a relatively rotatable member mounted thereon, said rotatable member terminating slightly within the extremity of said shaft, a cap adjustably secured to said rotatable member and adapted to bear upon the end of said shaft and a plurality of removable thin washers adapted to fill the space between the end of the rotatable member and said cap whereby adjustment to compensate for wear may be obtained by removing one or more of said washers and advancing said cap.

In testimony whereof, I have signed my name to this specification, in the presence of two subscribing witnesses.

MERLE P. CHAPLIN.
